UNITED STATES PATENT OFFICE.

JOHN T. GARTON, OF TORONTO, ONTARIO, CANADA.

FLOOR WAXER AND POLISHER.

Application filed September 9, 1921. Serial No. 499,382.

To all whom it may concern:

Be it known that I, JOHN T. GARTON, a subject of the King of Great Britain, and a resident of the city of Toronto, in the county 5 of York, Province of Ontario, Canada, have invented certain new and useful Improvements in Floor Waxers and Polishers, of which the following is a specification.

This invention relates to devices adapted 10 to apply wax to the floor and also to rub in the wax and polish the floor, and my object is to devise a hand power machine which will rub in the wax and which will polish by actuating the brush or brushes at a higher 15 rate of speed than is obtainable with the ordinary floor brush.

I attain my object by means of the constructions hereinafter described and illustrated in the accompanying drawings in 20 which—

Fig. 1 is a plan view of my improved waxer and polisher showing the waxing pad uppermost;

Fig. 2 is a longitudinal section of the 25 same; and

Fig. 3 an end elevation of the same.

In the drawings like numerals of reference indicate corresponding parts in the different figures.

30 1 is a frame, which is preferably shaped to enclose the parts of the apparatus to a considerable extent. At one end of this frame is journalled a crank shaft 2. A convenient arrangement is to form the bearings for this 35 crank shaft between the main part of the frame and a detachable part 1^a secured to the main portion of the frame by bolts 3.

On this crank shaft are secured the ground 40 wheels 4, which are preferably rubber tired to give a frictional grip on the floor surface over which the device is propelled. These wheels project, it will be noted, through openings in the frames 1 and 1^a, so that they will contact with the floor with the apparatus in the position shown in the drawings or turned upside down.

In the frame are suitably supported guides 50 adapted to guide tool carriers 5. The guides are conveniently formed of rods 6, one end of each rod being fitted in a hole in the end of the frame; while the other end is secured to the frame by a screw 7 passing through the end of the rod and screwed into the frame.

55 The tool carriers are each adapted to carry floor-finishing tools on opposite sides there-

of. In the drawings I show each carrier as formed of a plate provided with screw holes through which may pass screws 9 by means of which the back of a brush 10 may 60 be secured to the carrier. The back of the carrier is preferably formed with a circular wax pad carrier 11, through the wall of which are formed holes for the passage of the guide 6. The wax pad carrier 11 is 65 preferably formed with a bottom having keyhole slots 12 formed therein adapted to be engaged by the headed pins 13 secured to the pad base 14. It is evident that the pad bases are thus easily attached to or disconnected from the wax pad carrier. 70

Superimposed on each wax pad carrier is a wax pad 15 over which is placed a cloth 16, the edges of which may be clamped to the base by a slip ring 17. A cover 18 may 75 be slipped on over the ring 17 to protect the wax pad from dust and dirt when not in use.

To each tool carrier is pivotally connected one end of a connecting rod 19, the other end 80 of which is connected with one of the cranks 20 on the crank shaft 2. From this it follows that when the device is propelled over the floor, the ground wheels 4 will cause the tool carriers to be reciprocated, thus rapidly 85 moving the tools carried thereby over the surface of the floor.

Buffer springs 21 are preferably provided at the ends of the guides 6 to ease the shock caused by the reversal of movement of the 90 tool carriers and the parts carried thereby, and to assist in carrying the cranks over the dead centres.

Trunnions 22 are provided at the rear of the frame adapted to be engaged by the 95 handle bail 23, this bail being so proportioned that the device is readily turned either side up, the position of the handle relative thereto remaining substantially the same.

The device is used as follows. The wax 100 pad covers are removed and the device turned with the wax pads downwards. The weight of the apparatus is thus divided between the wax pads and ground wheels, sufficient weight being on the latter to drive 105 the tool carriers and sufficient weight on the former to cause the wax to be pressed out through the covering cloth and distributed over the floor surface. After the floor is sufficiently waxed, the position of the device is reversed and the floor thoroughly 110 brushed, sufficient of the weight of the ap-

paratus being carried by the brushes to make their operation effective. In finishing the floor a piece of cloth or carpet may be placed under the brush.

5. It will be noticed that each brush may rock laterally on its guide, and also that the guides have a loose fit in the holes in the carriers so that the floor finishing tools may readily rock to adapt themselves to any unevenness of the floor surface.

10. What I claim as my invention is:—

15. 1. A floor waxer and polisher comprising a frame; a reciprocable carrier adapted to carry a floor finishing tool at both its upper and lower sides; ground wheels mounted in the frame; and means whereby said ground wheels reciprocate the carrier, said wheels being adapted to contact with the floor with the frame positioned with either side of the 20 tool carrier lowermost.

20. 2. In a floor waxer and polisher, a reciprocable tool carrier adapted to be positioned with either of two sides lowermost and located towards one end of the frame and 25 adapted when the tool is in position to support part of the weight of the apparatus; ground wheels towards the opposite end of the apparatus adapted to support part of the weight of the apparatus; and means whereby said ground wheels may reciprocate the carrier with either of its aforesaid sides lowermost.

30. 3. A floor waxer and polisher comprising a frame; guides extending longitudinally of the frame; two carriers slidable on said guides; a crank shaft journalled on the frame; connecting rods pivotally connected to the cranks of the crank shaft and the carriers; floor finishing tools secured to opposite sides of each carrier; and ground wheels secured to said crank shaft, said wheels being adapted to contact with the floor with the frame positioned with either side of the tool carrier lowermost.

40. 4. A floor waxer and polisher comprising a frame; guides extending longitudinally of the frame; two carriers slidable on said guides; a crank shaft journalled on the frame; connecting rods pivotally connected to the cranks of the crank shaft and the carriers; cushion springs engageable by each carrier at each end of its stroke; floor finishing tools secured to opposite sides of each carrier; and ground wheels secured to said 45 crank shaft, said wheels being adapted to

contact with the floor with the frame positioned with either side of the tool carrier lowermost.

5. A floor waxer and polisher comprising a frame; a reciprocable carrier having a 60 brush secured to one side and a waxing pad detachably secured to the other side; ground wheels mounted in the frame; and means whereby said ground wheels reciprocate the carrier, said wheels being adapted 65 to contact with the floor with the frame positioned with either side of the tool carrier lowermost.

6. A floor waxer and polisher comprising a frame; a reciprocable carrier adapted to 70 carry a floor finishing tool at both its upper and lower sides, said carrier being mounted to rock sideways and endwise to permit the floor finishing tools to adapt themselves to inequalities of the floor surface; ground 75 wheels mounted in the frame; and means whereby said ground wheels reciprocated the carrier, said wheels being adapted to contact with the floor with the frame positioned with their side of the tool carrier lowermost. 80

7. A floor waxer and polisher comprising a frame; two guides extending longitudinally of the frame; a carrier slidable on each guide and oscillatable about the axis of the guide; a crank shaft journalled on the 85 frame; connecting rods pivotally connected to the cranks of the crank shaft and the carriers; floor finishing tools secured to opposite sides of each carrier; and ground wheels secured to said crank shaft, said wheels being adapted to contact with the floor with the frame positioned with either side of the carrier lowermost. 90

8. A floor waxer and polisher comprising a frame; two guides extending longitudinally of the frame; a carrier slidable on each guide, rockable lengthwise of the guide, and oscillatable about the axis of the guide; a crank shaft journalled on the frame; connecting rods pivotally connected to the 100 cranks of the crank shaft and the carriers; floor finishing tools secured to opposite sides of each carrier; and ground wheels secured to said crank shaft, said wheels being adapted to contact with the floor with the frame 105 positioned with either side of the tool carrier lowermost.

Signed at Toronto, Can., this 2nd day of Sept., 1921.

JOHN T. GARTON.
